UNITED STATES PATENT OFFICE.

JOHN J. BROCK, OF BROCKTON, MASSACHUSETTS.

PATENT-LEATHER-REPAIR OUTFIT.

No. 861,353.

Specification of Letters Patent.

Patented July 30, 1907.

Application filed March 16, 1907. Serial No. 362,665.

To all whom it may concern:

Be it known that I, JOHN J. BROCK, a citizen of the United States, residing at Brockton, county of Plymouth, State of Massachusetts, have invented a certain 5 new and useful Improvement in Patent-Leather-Repair Outfits, of which the following is a specification, reference being had therein to the accompanying drawings.

In the manufacture of patent and enamel leather shoes it is quite often the case that in some portions of 10 the upper, the enamel will crack or become damaged in some way, especially around the tips, the cracks being occasioned by bending the leather in forming the shoe. It is customary in such cases to sandpaper the part where the cracks occur to remove them and then 15 to apply a liquid filler to build up the sandpapered part to correspond with the original enamel, and then to apply a cutter or varnish as desired. The application of the filler or cutter has usually been made by the operator winding a cloth around his finger, tipping the bottle in which the filler is contained until a 20 small quantity adheres to the cork, then removing the cork from the bottle and rubbing onto the cloth a small portion of the filler which adhered to the cork, and then rubbing onto the shoe a portion of the filler which has 25 adhered to the cloth. This is a very inconvenient mode of operation, as it requires frequent tipping up of the bottle, removing the cork and then replacing the cork in the bottle each time that the cloth has to be moistened with the filler. It also exposes the contents 30 of the bottle to deposits of dust floating in the air whenever the cork is removed from the bottle and further it is difficult or impossible to keep the filler from getting daubed on the sides of the bottle.

The object of the present invention is to provide a 35 simple apparatus whereby the filler or other solution employed is protected from dust and at the same time a constant supply is kept in readiness for immediate application to the cloth whenever desired by the operator without exposing it to the atmosphere.

40 For convenience of description in the specification and claims I refer to the solution as filler, but intend that term to be construed broadly to cover any liquid solution.

The invention will be fully understood from the following description taken in connection with the accompanying drawings, and the novel features thereof will be particularly pointed out and clearly defined in the claims at the close of the specification.

In the drawings,—Figure 1 is a side elevation of an 50 apparatus embodying the invention. Fig. 2 is a vertical section of the apparatus shown in Fig. 1. Fig. 3 is a section on line 3—3 of Fig. 2. Fig. 4 is a side elevation partly in section showing the valve to the feed cup locked in a closed position by the supporting lever and 55 adjusting screw to keep the feed cup entirely closed when the apparatus is not in use, the main supply reser-

voir being omitted. Fig. 5 is a side elevation, partly in section, the main supply reservoir being omitted, and showing the ball valve slightly depressed by the finger of the operator as in using the apparatus. Fig. 6 is a 60 section of the feed cup on line 6—6 of Fig. 5. Fig. 7 is a plan of the feed cup with the ball valve omitted.

Referring to the drawings,—1 represents the main supply reservoir which may be simply a bottle in which the liquid filler is placed upon the market, the said 65 reservoir or bottle being mounted in an inverted position and provided with a cork or stopper 2 set into the neck 3 of the bottle, the cork being formed with a central aperture 4 through which a tube 5 is inserted forming a close fit to prevent the filler leaking out, the tube 70 5 connecting at its lower end with a cup 6 which by means of the tube 5 is kept supplied with the liquid filler from the reservoir 1. The passage through the tube 5 is preferably controlled by a valve or cock 7 which may be a common gas cock or any other suitable 75 valve to permit replenishing the contents of the cup 6 whenever needed.

The tube 5 is preferably formed with a flange 8 which forms a stop and a seat for the cork 2 or for the bottom of the reservoir if some sort of a receptacle other than that 80 of a corked bottle be used.

The cup 6 is provided with a cover top 9 which may either be detachable from the cup or preferably as shown in the drawings is made integral with the sides of the cup, the entrance to the cup preferably being 85 gained through the bottom 10 which may be made as a screw plug to screw into the threaded lower end of the cup.

Through the top 9 of the cup 6 is an aperture which is normally closed by a valve 11 seated upon a spring 12 90 whose tension is sufficient to keep the valve normally closed. Preferably this aperture is circular and the valve 11 is a sphere of somewhat larger diameter than the diameter of the aperture so that the ball valve 11 may protrude through the aperture from beneath without possibility of its coming entirely through. The spring 12 as shown is a wire spring doubled upon itself to form a loop 13, the two arms being formed with coils 14 to give tension and the two ends being secured to a support, as for instance to the top of the cup. The 100 form of the spring and manner of seating the valve thereon may be varied without departing from the invention. Secured to the under side of said cover top 9 are the two ears 16 within which is journaled a pivot 15 to which is secured a tilting lever 17. One end 105 of this lever 17 extends beneath the ball valve 11, that arm of the said lever being heavier than the other arm, so that normally the long arm will drop down as shown in Fig. 2 free from contact with the ball valve, thus allowing the ball valve to be pressed down by the 110 finger 18 when applied as shown in Fig. 1.

Passing through a screw threaded aperture in the

cover top 9 is a regulating screw 20 whose lower end engages the short arm of the lever 17. When the apparatus is in use, this screw 20 will be elevated sufficiently to allow the long arm of the lever to be free 5 from contact with the ball valve as shown in Fig. 2, so that the valve may when desired be opened as shown in Fig. 5. By setting down this screw 20, as shown in Fig. 4, it presses down the short arm of the lever and brings the long arm up against the under 10 side of the ball valve so as to retain the valve in its closed position.

The connection of the tube 5 with the cup 6 as shown is through a hollow projection 21 on one side of the cup, but the method of connection may be varied 15 without departing from the invention.

The apparatus should be mounted in such manner that the angle of inclination of the cup may be varied or may stand horizontal. When a thin liquid is used, such as that shown as cutter to cut down the edges of 20 the thick filler, it should preferably be adjusted so that the cup 6 will stand in nearly a horizontal position. When a filler is used which is of greater consistency than the cutter and which does not flow so freely, the apparatus should be adjusted so that the cup 6 will 25 stand at an inclination with its outer end lowermost as shown in Fig. 2, so that the filler may more-readily flow towards that end of the cup. In order to provide for this adjustability, it is pivotally mounted on a horizontal axis. As shown in the drawings, which is the 30 preferred form, the hollow projection 21 is formed with conical recesses 22 on opposite sides which form bearings for cone pointed pivots 23 projecting inwardly from standards 24 rising from the base 25. These cone pivots may be screw threaded so as to be adjusted to 35 give sufficient friction to hold the projection 21 and its connected apparatus at whatever position to which it may be adjusted, at the same time permitting the apparatus to be turned by a slight pressure so as to change the angle when desired.

40 When it is desired to apply some of the filler to the cloth which is used in rubbing on the shoes, the finger having the cloth 26 wrapped around it is applied to the valve 11, as shown in Fig. 1, the finger then being pressed down slightly to depress the valve against the 45 tension of the spring as shown in Fig. 5, and the ball is rotated on its seat by the pressure of the finger so as to bring to the outside the portion of the valve which has been previously immersed in the liquid filler within 50 the cup, and a sufficient quantity of the filler will adhere to the surface of the valve which can be rubbed off onto the cloth and then applied to the shoe. At the end of the day's work or when the apparatus is to be discontinued for any length of time, the screw 20 will be set down to bring the lever 17 up against the under side 55 of the valve, as shown in Fig. 4, so that the valve cannot be opened, and by the application of a little alcohol, or any other suitable cleaning fluid, the ball valve may be thoroughly cleansed and the apparatus may be left all ready for use whenever again desired.

60 While I have described the general reservoir as consisting of a bottle having a cork stopper through which is made a perforation to receive the tube, it is obvious that any reservoir with suitable aperture to fit the tube may be employed. I have described it as preferably 65 being used with a bottle because of its simplicity and

cheapness. In such case, of course, in order to connect the bottle with the apparatus, the apparatus will have to be inserted so as to make connection when the bottle is right side up.

It is obvious that a reservoir might be employed 70 which would be permanently attached to the tube 5 and have an opening in the top through which the filler could be poured into the reservoir.

I claim as my invention:

1. A patent leather repair outfit comprising a reservoir 75 to contain the filler, a feed cup, a tubular connection between the interior of said reservoir and said feed cup, said feed cup being provided with a cover having a valve controlled aperture therein, said aperture being normally closed by a spring seated valve.

2. A patent leather repair outfit comprising a reservoir to contain the filler, a feed cup, a tubular connection between the interior of said reservoir and said feed cup, said feed cup having a valve controlled aperture therein, said aperture being normally closed by a rotatable valve seated upon a spring within said cup and adapted to be depressed by pressure from without to partially open said aperture.

3. A patent leather repair outfit comprising a reservoir to contain the filler, a feed cup, a tubular connection between the interior of said reservoir and said feed cup, said feed cup being provided with a cover having a valve controlled aperture therein, said aperture being normally closed by a rotatable ball valve of larger diameter than said aperture seated upon a spring within said cup and normally held by said spring in a position to protrude up through said aperture and close the same.

4. A patent leather repair outfit comprising a reservoir to contain the filler, a feed cup, a tubular connection between the interior of said reservoir and said feed cup, said feed cup being provided with a cover having a valve controlled aperture therein, said aperture being normally closed by a valve seated upon a spring within said cup and normally held by said spring in a position to close said aperture, said valve being adapted to be depressed from without against the tension of said spring to partially open said aperture, and locking mechanism whereby said valve may be locked in its fully closed position.

5. A patent leather repair outfit comprising a reservoir to contain the filler, a feed cup, a tubular connection between the interior of said reservoir and said feed cup, said feed cup being provided with a cover having a valve controlled aperture therein, said aperture being normally closed by a rotatable valve seated upon a spring within said cup and adapted to be depressed by pressure from without to partially open said aperture, a locking lever pivoted within said cup having one arm which is adapted to engage the under side of said ball valve but which is normally so weighted as to be out of contact therewith and an adjusting screw which passes through said cup and engages with said lever, whereby said lever may be clamped up against said ball valve to hold it in a closed position.

6. A patent leather repair outfit comprising a reservoir to contain the filler, a feed cup, a tubular connection between the interior of said reservoir and said feed cup, said feed cup being provided with a cover having a valve controlled aperture therein, said aperture being normally closed by a rotatable ball valve of larger diameter than said aperture seated upon a spring within said cup and normally held by said spring in a position to protrude up through said aperture and close the same, a locking lever pivoted within said cup having one arm which is adapted to engage the under side of said ball valve but which is normally so weighted as to be out of contact therewith and an adjusting screw which passes through said cup and engages with said lever, whereby said lever may be clamped up against said ball valve to hold it in a closed position.

7. A patent leather repair outfit comprising a reservoir to contain the filler, a feed cup, a tubular connection between the interior of said reservoir and said feed cup, said feed cup being provided with a cover having a valve controlled aperture therein, said aperture being normally closed by a valve seated upon a spring within said cup and

- normally held by said spring in a position to close said aperture, said valve being adapted to be depressed from without against the tension of said spring to partially open said aperture, a locking lever pivoted within said cup 5 having one arm which is adapted to engage the under side of said valve but which is normally so weighted as to be out of contact therewith and an adjusting screw which passes through said cup and engages with said lever, whereby said lever may be clamped up against said valve 10 to hold it in a closed position.
8. A patent leather repair outfit comprising a reservoir to contain the filler, a feed cup, a tubular connection between the interior of said reservoir and said feed cup, having a valve controlled passage therethrough, said feed 15 cup being provided with a cover having a valve controlled aperture therein, said aperture being normally closed by a rotatable valve seated upon a spring within said cup and adapted to be depressed by pressure from without to partially open said aperture, a locking lever pivoted within 20 said cup having one arm which is adapted to engage the under side of said ball valve but which is normally so weighted as to be out of contact therewith and an adjusting screw which passes through said cup and engages with said lever, whereby said lever may be clamped up against 25 said ball valve to hold it in a closed position.
9. A patent leather repair outfit comprising a reservoir to contain the filler, a feed cup, a tubular connection between the interior of said reservoir and said feed cup, having a valve controlled passage therethrough, said feed 30 cup being provided with a cover having a valve controlled aperture therein, said aperture being normally closed by a rotatable ball valve of larger diameter than said aperture seated upon a spring within said cup and normally held by said spring in a position to protrude up through said 35 aperture and close the same, a locking lever pivoted within said cup having one arm which is adapted to engage the under side of said ball valve but which is normally so weighted as to be out of contact therewith and an adjusting screw which passes through said cup and engages with said lever, whereby said lever may be clamped up against 40 said ball valve to hold it in a closed position.
10. A patent leather repair outfit comprising a reservoir to contain the filler, a feed cup, a tubular connection between the interior of said reservoir and said feed cup 45 having a valve controlled passage therethrough, said feed cup being provided with a cover having a valve controlled aperture therein, said aperture being normally closed by a rotatable ball valve of larger diameter than said aperture
- seated upon a spring within said cup and normally held by said spring in a position to protrude up through said aperture and close the same, said valve being adapted to be depressed from without against the tension of said spring to partially open said aperture, a locking lever pivoted within said cup having one arm which is adapted to engage the under side of said ball valve but which is normally so weighted as to be out of contact therewith and an adjusting screw which passes through said cup and engages with said lever, whereby said lever may be clamped up against 50 said ball valve to hold it in a closed position.
11. A patent leather repair outfit comprising a reservoir to contain the filler, a feed cup, a tubular connection between the interior of said reservoir and said feed cup, said feed cup being provided with a cover having a valve controlled aperture therein and a support to which said combined apparatus is pivoted on a horizontal axis whereby 55 said apparatus may be rocked to adjust the feed cup to a horizontal position or to an inclined position as desired.
12. A patent leather repair outfit comprising a reservoir to contain the filler, a feed cup, a tubular connection between the interior of said reservoir and said feed cup, said feed cup being provided with a cover having a valve controlled aperture therein, said reservoir comprising a bottle in an inverted position provided with a stopper having a 60 perforation therethrough into which said tube is inserted.
13. A patent leather repair outfit comprising a reservoir to contain the filler, a feed cup, a tubular connection between the interior of said reservoir and said feed cup, said feed cup being provided with a cover having a valve controlled aperture therein, said reservoir comprising a bottle in an inverted position provided with a stopper having a 65 perforation therethrough into which said tube is inserted, said tube being provided with a flange which forms a seat for the stopper of said reservoir.
14. A patent leather repair outfit comprising a reservoir to contain the filler, a feed cup, a tubular connection between the interior of said reservoir and said feed cup, said feed cup being provided with a cover having a valve controlled aperture therein, said feed cup being provided with a screw plug in the bottom.
- In testimony whereof I affix my signature, in presence 70 of two witnesses.

JOHN J. BROCK.
